UNITED STATES PATENT OFFICE.

GEORGE CONRAD LUZ WEGUELIN, OF CHERTSEY, ENGLAND.

BUREAU.

Application filed March 28, 1922. Serial No. 547,364.

To all whom it may concern:

Be it known that I, GEORGE CONRAD LUZ WEGUELIN, a subject of the King of Great Britain, residing at Bridge House, Chertsey, 5 Surrey, England, have invented new and useful Improvements in Bureaus, of which the following is a specification.

This invention relates to a bureau of the type having a hinged flap which when open 10 may serve to write on.

According to this invention a bureau is provided below the flap with two sets of drawers, each set being fast with a door so that when the doors are closed the drawers 15 lie transversely front to front, while the doors are connected to the flap by mechanism such that the opening of the flap opens the doors to form a pedestal bureau and shutting the flap closes the doors.

20 The invention is illustrated in the accompanying drawings in which Figure 1 is a sectional elevation of the bureau open and Figure 2 a sectional plan of the same, while Figures 3 and 4 are similar views of the 25 bureau closed, the flap being removed in Figure 4.

In the drawings, 1 is the flap, 2 the doors, 3 the drawers fast therewith; 4 are links 30 pivoted to the flap and to slides 5 mounted on guides 6 while a rod 7 is fast with the slides; on the rod 7 is a pair of racks 8 gearing with quadrants 9 each of which is 35 screwed on the top of one set of drawers 3.

On opening the flap the links 4 are operated so moving the slides 5, the rod 7 and racks 8 forward; the racks gearing with the

quadrants 9 will cause the drawers 3 and the doors 2 fast therewith to turn about the door hinges and move from the position shown in Figures 3 and 4, in which the 40 bureau has the appearance of a cupboard, to that shown in Figures 1 and 2, i. e. a writing bureau with knee holes.

What I claim is:—

1. In a bureau, the combination with a 45 flap, of two sets of drawers movably mounted below the flap, doors, one of which is fast to one set of drawers and the other of which is fast to the other set of drawers, and mechanism connecting the flap to the 50 doors such that the opening of the flap moves the doors to open position and the drawers to accessible position, while the closing of the flap moves the drawers to a position in which they lie transversely front 55 to front and closes the doors.

2. In a bureau, the combination with a flap, of two sets of drawers movably mounted below the flap, doors, one of which is fast to one set of drawers and the other of which is fast to the other set of drawers, 60 quadrants connected to the drawers, racks meshing with said quadrants, slides with which the racks are mounted to move, and links connecting the flap to said slides, 65 whereby the opening of the flap moves the doors to open position and the closing of the flap closes the doors.

In testimony that I claim the foregoing as my invention I have signed my name this 70 16th day of March, 1922.

GEORGE CONRAD LUZ WEGUELIN.
